Gottlieb Thülemeyer

UNITED STATES PATENT OFFICE.

GOTTFRIED THULEMEYER, OF NEW YORK, N. Y.

IMPROVEMENT IN FURNACES FOR REBURNING BONE-BLACK.

Specification forming part of Letters Patent No. 40,371, dated October 20, 1863.

To all whom it may concern:

Be it known that I, GOTTFRIED THULEMEYER, of the city, county, and State of New York, have invented a new and useful Improvement in Furnaces for Reburning Bone-Black, &c.; and I do hereby declare that the following is a full, clear, and exact description of the same, reference being had to the accompanying drawings, forming a part of this specification, in which—

Figure 1 represents a transverse vertical section of my invention, taken in the plane indicated by the line $x x$, Fig. 3. Fig. 2 is a longitudinal vertical section of the same, the line $w w$, Fig. 3, indicating the plane of section. Fig. 3 is a plan or top view of the same, partly in section. Fig. 4 is a partial side elevation of the same.

Similar letters of reference in the several views indicate corresponding parts.

This invention relates to certain improvements in the internal arrangement of the furnace whereby the heat is equally distributed all round the retorts and throughout their entire length, and consequently an even and uniform heating of the bone-black or other substance contained in the retorts is insured.

The invention also relates to a peculiarly-shaped retort, whereby a large quantity of bone-black or other material can be exposed simultaneously to the heat of the fire in a stratum of uniform and small thickness, and the whole mass can be heated evenly and uniformly with a comparatively small quantity of fuel.

To enable those skilled in the art to make and use my invention, I will proceed to describe it.

A represents a furnace, built up of brick or any other suitable material, and provided with two fire-places, B B'.

C C are the retorts, which are made in the shape of horseshoes, as clearly shown in Fig. 3 of the drawings. The cross-section of each of these retorts presents a long thin space capable of receiving a comparatively large quantity of bone-black or other material, and spreading the same in a uniform thin stratum over a large area, so that the heat can easily penetrate the entire mass. These retorts are arranged in two or more rows between the fire-places B B', and they rest upon the bot-

tom plate, D, of the furnace, and are steadied by a dividing-plate, E, which may be made in sections to facilitate its adjustment.

The bottom plate, D, is protected by a false bottom, F, having an air-space, a, that prevents the bottom ends of the retorts from being overheated or burned.

The partition-plate E completely separates the space below it from that above, and it extends back into the recesses between the two branches of each retort, leaving apertures b, through which the heat from the fire and the products of combustion must pass in order to reach the holes c in the side walls of the furnace. These holes lead through said side walls into flues d, which are built between the double walls of the furnace, causing the heat or products of combustion to descend into the horizontal flues e, which extend to the ends of the furnace and communicate with the inclined flues f, leading to the chimney. By this arrangement the heat, after passing up through the apertures b, is compelled to pass all round each of the retorts in order to reach the holes c in the side walls, and every part of each retort is then kept at a uniform temperature throughout the whole furnace. The bone-black can thus be heated slowly and uniformly throughout every retort, and the restoration of the same can be effected with a comparatively small expenditure of fuel, with little or no loss of bone-black, and in the most perfect manner.

The retorts are closed on the top by a cover, G, common to all, which rests loosely on the top edge of the brick wall, and which is provided with flanges g, projecting down into or over the several retorts, as clearly shown in Figs. 1 and 2. This cover may be made of sheet-iron or any other suitable material, and it may be made in several sections to facilitate its removal. By removing this cover access can be had to the interior of the retorts.

The retorts are open at the bottom, and they empty into feet H, which discharge through slides h. When the bone-black or other material has been heated sufficiently, it is let down into the feet H, where it cools, and when cold it is withdrawn through the slides h.

What I claim as new, and desire to secure by Letters Patent, is—

1. The horseshoe-shaped retorts C, ar

ranged in the furnace A, in the manner and for the purpose substantially as herein shown and described.

2. The partition-plate E, when made whole or in sections, and provided with apertures b, in combination with the retorts C and furnace A, all constructed and operating substantially as and for the purpose set forth.

3. The arrangement of one or more series of

retorts, C, between two fire-places, B B', in combination with the partition-plate E, side flues, d e, and end flues, f, all constructed and operating in the manner and for the purpose substantially as specified.

GOTTFRIED THULEMEYER.
